UNITED STATES PATENT OFFICE

164,300

HANDLE FOR FLUSH TANK LEVER

David E. Gulick, Kittanning, Pa., assignor to
Eljer Co., Ford City, Pa.

Application April 23, 1948, Serial No. 145,928

Term of patent 14 years

(Cl. D91—3)

To all whom it may concern:

Be it known that I, David E. Gulick, a citizen of the United States, residing at Kittanning, Pennsylvania, have invented a new, original and ornamental Design for a Handle for Flush Tank Lever, of which the following is a specification, reference being had to the accompanying drawing, forming part thereof.

Fig. 1 is a front elevational view of a handle for flush tank lever, showing my new design;

Fig. 2 is a side elevational view thereof; and

Fig. 3 is a perspective view thereof.

I claim:

The ornamental design for a handle for flush tank lever, as shown.

DAVID E. GULICK.
